R. R. MORRILL

OIL BURNER

Filed April 8, 1922

Inventor
Richard R. Morrill
By G. R. Cornwallatty.

UNITED STATES PATENT OFFICE.

RICHARD REED MORRILL, OF PALO ALTO, CALIFORNIA, ASSIGNOR TO OLIVER OIL-GAS BURNER AND MACHINE COMPANY, OF ST. LOUIS, MISSOURI, A CORPORATION OF DELAWARE.

OIL BURNER.

Application filed April 8, 1922. Serial No. 550,821.

To all whom it may concern:

Be it known that I, RICHARD REED MORRILL, a citizen of the United States, residing at Palo Alto, county of Santa Clara, 5 State of California, have invented a certain new and useful Improvement in Oil Burners, of which the following is a full, clear, and exact description, such as will enable others skilled in the art to which it appertains to make and use the same, reference being had to the accompanying drawings, forming part of this application.

This invention relates to new and useful improvements in oil burners; and the objects of the invention are to provide an oil burner which can be easily installed, is of durable construction and which will efficiently burn oil without the formation or deposition of carbon in the burner tubes or 20 in the connections leading thereto.

Other objects of the invention are to provide a burner detachably mounted in a suitable housing, and means for regulating the ingress of air to the burner and to the 25 drier desired to be heated by the burner, and to generally improve upon and simplify the construction of oil burners of the class described.

With these and other objects in view, my 30 invention consists in certain novel features of construction and arrangements of parts hereinafter described and claimed, and illustrated in the accompanying drawings, in which:—

35 Figure 1 is a front elevation of the oil burner partly in section.

Figure 2 is a horizontal cross section taken on line 2—2 of Figure 1.

40 Figure 3 is a vertical cross section through the burner.

Figure 4 is a horizontal cross section through the vaporizer and the burner and showing means for closing the open ends thereof.

45 Figure 5 is a vertical cross section through a modified form of the oil burner.

Figure 6 is a front elevation of same.

Referring by numerals to the accompanying drawings, 10 designates a box-like housing open at both ends to form a combustion chamber 11. The rear end of housing 10 is provided with a laterally projecting flange 12 which is designed to be placed against

the wall of the drier or other apparatus desired to be heated, with the open rear end 55 of chamber 11 communicating with an opening formed in said drier, as indicated in dotted lines at 14.

The side walls 15 of housing 10 are formed with registering slots 16 which are 60 open at their forward ends for the reception of a casting 17. This casting extends transversely through chamber 11 and its ends rest in slots 16. Casting 17 consists of two preferably tubular members which are 65 parallel with each other. The forward one of these members constitutes a burner 18. The other member which is spaced rearwardly and upwardly relative to burner 18, is a vaporizer 19 which is designed to be 70 heated by burner 18, whereby the oil contained in member 19 is converted into gas.

One end of vaporizer 19 is connected by a pipe 20 to a suitable oil reservoir, and interposed in this pipe and controlling the 75 flow of oil from the reservoir to the vaporizer is a needle valve 21 manually operable by handle 22 and having a dial 24 by means of which the positioning of the handle 22 can be guided.

80 The corresponding end of burner 18 is closed by a plug 25 screw-seated therein. The opposite ends of burner 18 and vaporizer 19 are closed by a plate 26 held in position thereon by a nut 27 which engages the 85 projecting threaded end of a bolt 28, the latter being screw-seated in casting 17.

In order to form a fluid tight seal between the burner and the vaporizer, a gasket 29 made of suitable fire-resistant material is placed between plate 26 and the ends 90 of burner 18 and vaporizer 19.

Integrally formed with burner 18 and vaporizer 19 near the ends thereof remote from supply pipe 20 is a passageway 17^a 95 which connects the interior of the vaporizer with the burner.

In the manufacture of casting 17, a rib 30 is cast integral with the burner and vaporizer, and is then sawed through as indicated 100 at 30^a in order to provide for expansion of the metal when the casting is used.

A trough 31 is formed integral with and extends forwardly from burner 18 and is designed to receive oil from said burner 105 through orifices 32 formed in the top of the

latter. One end of trough 31 is provided with an opening through which access may be gained to the passageway 17^a, and this opening is normally closed by plug 33 5 screw-seated therein.

An overflow pipe 34 is tapped in the front wall of said trough near the top thereof and serves to convey the excess oil, after it reaches a certain predetermined level in said 10 trough, to an overflow tank. A closure plate or deflector 35 is pivotally supported in the side walls 15 by means of a rod 36 and is adjustable in position by a handle 37 whereby the size of the opening in the forward 15 end of housing 10 may be adjusted to regulate the supply of air to burner 18 and the drier desired to be heated. Plate 35 can be locked in its adjusted position by a screw 38 which is screw-seated in housing 10 and has 20 its lower end adapted to engage rod 36.

The top wall of housing 10 is formed with a plurality of inwardly disposed ribs 10^a which are embedded in and serve to hold in position a layer of asbestos or analogous 25 material 39 with which the upper portion of the housing 10 is lined.

In the modified form shown in Figures 5 and 6, the housing 40 is of cylindrical shape and open at both ends. The oil supply pipe 30 41 has its end portion 42 bent in the form of a U which is arranged in said housing with its parallel portions occupying a horizontal position. The extreme end of this pipe is closed by a perforated cap 44 which 35 constitutes the burner.

When pipe 41 is in position in housing 40, the burner cap 44 occupies the front end of said housing below the supply pipe 41 so that the oil contained in the bent portion 42 40 will be heated and converted into gas by burner 44.

In the operation of my device, the trough 31 is flooded with oil, which is then ignited, and the heat generated by combustion of the 45 oil heats burner 18 and vaporizer 19 and converts the oil contained therein into gas which will escape under pressure from burner 18 through orifices 32. This gas is then ignited and the flames will be deflected inwardly to- 50 wards the drier end of the housing thereby passing over vaporizer 19, and maintaining it at the proper temperature, so that the oil entering said vaporizer will be vaporized.

The air is admitted into chamber 11 through 55 the inlet opening formed in the forward end of said housing and controlled by the closure plate 35 and in passing through said chamber will be heated by burner 18 so that before entering the drier it will be raised 60 to the proper temperature.

That portion of rod 28 which is engaged by nut 27, being located exteriorly of casting 17, will not become corroded so that the proper working engagement will be main- 65 tained between it and nut 27 and no diffi-

culty will be experienced in removing the plate 26 from its position on the casting 17.

The location of plate or damper 26 in the housing 10 permits the quantity of air used directly through the burner to be changed 70 without lowering its velocity. By changing the number and size of orifices, the capacity of the burner is changed as is also the time required for complete combustion. Thus, the supply of air and oil are properly controlled and the burner is consequently more 75 flexible and efficient in operation.

While I have shown and described the preferred form of my burner, it is obvious that 80 various changes in the size, form and arrangement of parts of my improved burner can be made and substituted for those herein shown and described without departing from the spirit of my invention.

What I claim is:

1. An oil burner comprising a housing open at both ends, a burner supported in said housing, a vaporizer supported rearwardly of said burner and having communication therewith, and an oil supply pipe connected to said vaporizer, said burner and said vaporizer being arranged at different horizontal planes so that said vaporizer is heated by said burner and the oil contained 90 therein is converted into gas. 95

2. An oil burner comprising a housing open at both ends, a burner supported in the forward end of said housing, a vaporizer supported rearwardly of said burner and having communication therewith, an oil supply pipe connected to said vaporizer, and adjustable closure means for regulating the inlet of air to said housing. 100

3. An oil burner comprising an open ended housing, a burner arranged in the forward end of said housing and provided with an oil receiving trough, a vaporizer arranged in said housing rearwardly of said burner, and occupying a higher horizontal plane relative thereto, there being a passageway provided between said vaporizer and said burner, an oil supply pipe connected to one end of said vaporizer, and a plate detachably held in position for closing the opposite end of said vaporizer and the corresponding end of said burner. 110 115

4. An oil burner comprising an open-ended housing, a burner arranged in the forward end of said housing and provided with an oil receiving trough, a vaporizer arranged in said housing rearwardly of said burner and occupying a higher horizontal plane relative thereto, there being a passageway provided between said vaporizer and said burner, an oil supply pipe connected to one end of said vaporizer, a plate detachably held in position for closing the opposite end of said vaporizer and the corresponding end of said burner, closure means 120 adjustably mounted in the forward end of 125 130

said housing for controlling the ingress of air to said housing, and means for locking said closure means in adjusted position.

5. An oil burner comprising a housing open at both ends and having registering slots formed in the side walls, adjustable closure means arranged in the forward ends of said housing, a tubular vaporizing member arranged in said housing and having its 10 ends resting in said slots, a perforated burner formed integral with said vaporizing member and having communication therewith, said burner occupying a position forwardly of and slightly below the plane of 15 said vaporizing member, an oil supply pipe leading into said vaporizing member, a closure member for closing one end of said vaporizing member and the corresponding 20 end of said burner, and means for detachably securing said closure member in position.

6. An oil burner comprising a housing open at both ends, adjustable means for closing the end of said housing, a casting detachably arranged in said housing and having formed therein a vaporizing chamber and a burner in communication therewith, the latter being arranged forwardly of and below the plane of said vaporizing chamber 25 so that the ignited gas from said burner has to pass over said vaporizing chamber and heat it, means for supplying oil to said vaporizing chamber, and a plate detachably secured to said casting for closing one end 30 of said vaporizing chamber and the corresponding end of said burner.

7. An oil burner comprising a housing having a combustion chamber therein, a

burner supported in said combustion chamber, a vaporizer arranged adjacent to said burner and having communication therewith, fluid supply connections connected to said vaporizer, and closure means on said housing for controlling the quantity of air supplied to said combustion chamber. 40 45

8. A burner comprising a housing having a combustion chamber formed therein, a burner arranged in said combustion chamber, a vaporizer arranged adjacent to said burner and having communication therewith, a fluid supply means connected to said vaporizer, and closure means for controlling the supply of air to said combustion chamber, said burner being adapted to have formed therein the required number of discharge openings of proper size. 50 55

9. An oil burner comprising a burner housing, a burner located in one end of said housing, an oil vaporizer arranged rearwardly of said burner and in communication therewith and a damper plate for regulating the supply of air to said burner housing by varying its volume without materially affecting its velocity. 60

10. An oil burner comprising a housing open at its ends, a burner located in one end of said housing, an oil vaporizer arranged rearwardly of said burner and having communication therewith, and a closure plate arranged in the forward end of said housing for regulating the supply of air to said housing by varying the volume of air without materially affecting its velocity. 65 70

"In testimony whereof I hereunto affix my signature this 30th day of March, 1922.

RICHARD REED MORRILL.
